STRUCTURAL PANEL

Darrell W. Craik, Escondido, Calif., assignor to
Teledyne, Inc., Los Angeles, Calif.

Filed Sept. 21, 1972, Ser. No. 290,844

Term of patent 14 years

Int. Cl. D25—01

U.S. Cl. D54—2 A

FIG. 1 is a perspective view from beneath and looking upward of a structural panel in accordance with my design.

FIG. 2 is a sectional view of a structural panel in accordance with my design taken along the lines 2—2 of FIG. 1.

I claim:

The ornamental design for the structural panel, as shown.
